Application January 10, 1955, Serial No. 480,949

6 Claims. (Cl. 122—356)

This invention relates to improvements in heaters for fluids and refers more particularly to heaters in which tubular heat exchange elements are vertically suspended centrally of a narrow combustion zone dividing the zone into two separate vertical ducts for the free passage of combustion gases from bottom to top of the zone and utilizing inwardly sloped or inclined side walls to effect more even and uniform distribution of the radiant and convection heat.

At the temperatures now employed in some heating operations, even with the improved metallurgy that has been developed, it is advantageous to have the heating elements vertically suspended, which arrangement reduces difficulties encountered when tubes are horizontally positioned or when vertical tubes are supported from below. Other problems continually confronting engineers responsible for heater design is the uniform distribution of radiant and convection heat over the heat exchange surfaces, the free unobstructed flow of combustion gases through the heater, and accurate control of the heat supplied to the combustion chamber and an efficient adjustment of the amount of heat to all parts of the combustion chamber and heat exchange elements.

An object of the invention therefore is to provide a heater construction in which combustion gases have a free unobstructed flow from the sources of heat through the combustion chamber and a tube arrangement adapted to efficiently extract a maximum amount of heat from the gases during their passage through the combustion zone.

Another object is to furnish an arrangement of the heat exchange elements so that a maximum surface will be exposed both to convection and radiant heat.

A further object is to provide a construction or design in which the reflecting walls of the furnace or heater will uniformly distribute the radiant and convection heat onto the heat exchange surfaces.

Another object is to utilize the air supplied to the heat sources and forming a part of the combustion gases as an insulating blanket around the side walls of the heaters to thereby preheat such air and effect more efficient combustion. Other and further objects will appear from the description which follows.

In the accompanying drawings which form a part of the instant specification there is shown an embodiment of the invention, and like reference numerals are used to indicate like parts in the various views.

Fig. 1 is a side elevation of a heater embodying the invention with parts broken away to show the manner of suspending the tube bank centrally thereof.

Fig. 2 is an end view of the heater shown in Fig. 1 with parts broken away.

Fig. 3 is an enlarged detail of the tube hanger construction.

Fig. 4 is a view taken along the line 4—4 in Fig. 3.

Fig. 5 is an enlarged perspective detail of a tube hanger ring.

2

Fig. 6 is a plan view of a section of the floor of the heater taken along the line 6—6 in Fig. 2.

Referring to the drawings, and particularly to Figs. 1 and 2, upon piers 10 are transverse I-beams 11 which support the floor 12. The side and end walls of the heater comprise a metal frame made up of vertical members 13 and horizontal cross members 14 which carry the exterior panels 15 and blocks of fire resistant ceramic material 16 which form the inner walls of the heater and reflecting walls of the combustion chamber. The top enclosure is likewise refractory material shown diagrammatically at 17 supported by suitable longitudinal and horizontal framework indicated at 18. A breeching comprising tubular ducts 19 and 19a conduct the combustion gases from the top of the furnace into a stack 20. Dampers 21 in the breeching are manually controlled from cranks 22 through cables 23 and pulleys 24 mounted upon the damper shafts. Between the inner walls of fire brick 16 and the outer jacketing panels 15 are air ducts 25 provided with an inlet 26 extending longitudinally of the heater near the top and horizontal ducts 25a beneath the floor 12 whereby air is drawn from the atmosphere through the inlets 26, passed downwardly between the inner and outer walls of the heater and discharged into burners 27 where it is combined with fuel supplied through pipes 28 to form the combustion gas used in the heater. These burners 27 are closely spaced at intervals along the bottom of the heater as shown in Fig. 6.

Running longitudinally of the heater and suspended from the top frame 18 is an I-beam 29 shown best in Fig. 2. From this I-beam are suspended the heat exchange elements through which fluid is passed in transferring heat from the combustion chamber to such fluid. The heat exchange elements consist of a bank of vertical tubes 30 arranged in rows centrally of the heater with the tubes in the separate banks staggered with relation to the tubes in the other bank so a maximum amount of surface will be exposed to the heating gases passing upwardly through the separate vertical ducts formed by the centrally positioned tube bank. In other words, the vertical tubes in one row are arranged opposite the space between the tubes in the adjacent row so convection and radiant heat from the two vertical combustion compartments or passageways between the burners 27 and the outlet breeching is distributed uniformly over the tube surfaces.

At the top the return bends 30 joining the tubes are suspended from beam 29 by hanger rods 31 and rings 32. The lower ends of the rods have apertured yokes 31a which straddle lugs 32a on top of rings 32. Pins 33 held by cotter pins extending through the holes in the bifurcated portions of the hanger and the eyes in lugs 32a furnish an easily removable connection between the hanger rods and the tubes. An inlet connection 34 to the initial tube of the bank provides a means by which fluid is supplied to the tube bank and a corresponding connection 35 discharges the fluid after it has been heated. These connections are conveniently arranged at a level so they may be easily manifolded to the tube bank in order that the fluid may be supplied to a plurality of tubes simultaneously and discharged from a plurality of tubes at the discharge side of the bank. Such arrangement permits altering the capacity of the heater with but little structural change.

The heat sources 27 shown as burners in Fig. 6 are closely spaced in the floor of the furnace or heater so all or any number may be used on either side of the tube bank offering a flexible control of heat to the combustion zone.

In the floor and enclosing the lower end of the tube and return bends is an insulated tunnel 36 running longitudinally of the heater. In this tunnel are access plates 36a through which tubes may be removed from below, since the access plates run along the bottom of the tunnel.

and the heater is raised sufficiently on the piers to permit handling of the tubes through these lower access openings.

The inner side reflecting walls of the heater are sloped or inclined at a proper angle inwardly from bottom to the top of the combustion chamber for the purpose of more uniform distribution of radiant and convection heat upon the surfaces of the tubular elements 30. At the lower part of the combustion chamber the reflecting walls are relatively remote from the tubes where the heat is the greatest. The inclination of the walls is such that the reflecting surface is closer to the tubes near the top where the reflected heat is least. The convection heat absorption is a function of the cross sectional area of the furnace and as the temperature of the convection gases decreases the cross sectional area is also decreased, to maintain a constant heat absorption. By inclining the walls or sloping the walls inwardly at a predetermined angle from bottom to top the vertical ducts on opposite sides of the tube bank are shaped so both radiant and convection heat is more uniformly and evenly distributed upon the surfaces of the heat exchange element. The angle at which the side walls are sloped or inclined will depend to a great extent upon the height of the combustion chamber and the length of the tubes or heat exchange elements which are serviced. As previously suggested, air supplied to the burners or heat sources is first circulated through the plenum chambers or ducts 25 surrounding the side walls of the heaters and besides serving as insulating blanket preheats the air before introduction to the combustion chamber.

From the foregoing, it will be seen that the invention is one well adapted to attain all of the ends and objects hereinbefore set forth, together with the other advantages which are obvious and which are inherent to the structure. The previous description is intended to be explanatory of a construction which embodies the invention, but it should be noted that various changes in the size, shape and materials used may be made, as well as the details of the illustrated construction, within the scope of the appended claims without departing from the spirit of the invention.

Likewise, it will be understood that certain features and subcombinations are of utility and may be employed without reference to other features and subcombinations. This is contemplated by and is within the scope of the claims.

Having thus described our invention, we claim:

1. In a tubular heater for fluids, the combination with side walls, a floor, a top enclosure with flue gas breeching and a stack, tube support means fixed within the heater adjacent the top thereof, a bank of vertical tubes suspended from the tube support means adjacent the top of the heater and arranged centrally thereof, said bank of tubes extending from the floor to substantially the top of the heater the vertical tube bank comprising at least one row of tubes with adjacent tubes positioned so closely

next one another as to partition the combustion zone of said heater substantially into two vertical gas ducts extending from the floor to the top of the heater, tubular return bends detachably connected at the tops and bottoms of the tubes to form a continuous flow-way therethrough from one end of the bank to the other, inlet and outlet connections to the bank extending through the wall of the heater, means for supporting the bank from the tube support means comprising a plurality of individual releasing suspension means connected to a plurality of upper bends of the bank, removable access means in the floor of the heater whereby tubes may be removed and replaced therethrough, and heat sources in the bottom of each of said ducts.

15 2. A heater as in claim 1 wherein the individual suspension means are connected individually to each upper bend of the bank to individually support each loop of tubing in the bank.

20 3. A heater as in claim 1 wherein the side walls of the heater are sloped inwardly from bottom to top throughout the combustion zone whereby radiant and convection heat is uniformly distributed over the surfaces of the tubes in said tube bank, means forming plenum chambers adjacent the side walls and extending essentially the entire length thereof with air inlets at the top of said plenum chambers and discharge outlets through the floor of the heater whereby the air stream through said plenum chambers aids in insulating the side walls and provides preheated air to the heat sources.

25 4. A heater as in claim 1 wherein said heat sources in the bottom of each duct comprise a plurality of individual heat sources spaced along the width of the bank whereby heat may be applied through each individual source to a limited width of the tube bank whereby to permit differential heating across the width thereof.

30 5. A heater as in claim 1 wherein said inlet and outlet connections are arranged in the same horizontal plane as the upper tube bends whereby manifolding of the tubes in multipass arrangement is facilitated.

35 6. A heater as in claim 1 wherein the vertical tube bank comprises at least a double row of tubes, the tubes in each row staggered with respect to the tubes in the adjacent row or rows yet positioned apart one from another a distance not greater than the outer diameter of the tubes, the tube bank partitioning the combustion zone of said heater substantially into two vertical gas ducts extending from the floor to the top.
